UNITED STATES PATENT OFFICE.

LUTHER HILL, OF LOS ANGELES, CALIFORNIA.

ANTIRATTLE WINDOW LOCK.

Application filed February 23, 1923. Serial No. 620,661.

This invention is an improvement in that class of anti-rattle and burglar proof locks for window sashes in which a friction device is slidably mounted on a base and is operable by a lever pivoted to the base, to engage one window sash of a pair of sashes, to the other sash of which pair the base is fixed.

Said locks are applicable to a window sash singly to prevent rattle, or in pairs to insure against entrance of burglars, and an object is to adapt the improvement to both right and left members of a pair of the locks so that the release will operate satisfactorily in either and both of such locks when properly installed on a sash.

An object is to provide a simple and effective construction whereby the lock can be easily released.

A feature of my invention is to provide a screw for the actuating lever which screw serves to secure the lock to the sash.

Other objects, advantages and features of invention may appear from the accompanying drawing, the subjoined detail description and the appended claim.

The accompanying drawing illustrates the invention.

Figure 1 is a broken perspective view showing a pair of window locks equipped with my improvement and installed on a window; a fragment of which is shown. The lock at the left is shown as having been moved to unlocked position while that at the right is in locking position in solid lines and unlocking position in dot and dash lines.

Fig. 2 is a plan of the window lock shown in the left of Fig. 1. A fragment of the upper sash and the frame are shown in section. Dot and dash lines indicate the parts in locking position.

Fig. 3 is a section on line x^3 , Fig. 2.

Fig. 4 is a section on line x^4-x^5 , Fig. 2, showing the device in locking position.

Fig. 5 is a section on line x^4-x^5 , Fig. 2, showing the device in unlocked position.

Fig. 6 is an elevation taken from the left of Figs. 2 and 3.

The lock to which this improvement is applied comprises three parts, as base 1, a locking slide 2 and locking lever 3 connected to each other and to the top of the

lower sash a of a window by the screw 4 which acts as a pivot for the lever 3. The base 1 is attached to said lower sash by 55 screws 5. The slide 2 is provided with a slot 6 through which the screw 4 is inserted and flanges 7 upturned from the base 1 form a guideway for the slide 2. Said slide 2 is provided with frictional sash engaging 60 means 8 consisting of a block 9 preferably of rubber mounted in a holder 10 that is formed by an upturned end of the slide pressed into shape. The engaging means 8 is moved into sash engaging position by 65 means of the lever 3 which is rounded at one end 11 to engage the means 8, and is provided at the other end with a handle or thumb piece 12, and is adapted to turn on the screw 4.

In the present invention I have provided the slide 2 with a shoulder, knob or protuberance 14 struck up from the slide and so positioned that when the lever is moved from locking position it will act upon the 75 knob to retract the slide 2 with its means 8 from sash engaging position.

The manner of applying the locks to the window is substantially the same as that employed heretofore and the operation is 80 the same excepting that when a handle 12 is turned toward the center of the window, the same being toward the right of the left-hand lock and toward the left of the right-hand lock, the lever contacts with the shoulder boss or knob 14 and operates a slide.

Said boss or knob is struck up from the slide close to one edge thereof and at such a distance from block 10 to allow the rounded end of the lever to fit between the 90 block and the projection 14, so that the action of the lever will be such as to easily actuate the slide to perform its function.

I claim:

In an anti-rattle window lock, comprising 95 a base, screws adapted to extend through said base into the upper edge of the lower sash of a window, integrally formed upwardly extending flanges on the sides of said base, a slotted slide adapted to move longitudinally between said flanges, a holder integral with said slide and arranged at one end thereof, a rubber block carried by said holder, a lever, a screw extending through

the lever and base and adapted to be screwed into a sash through the slot in said slide to pivot said lever, said lever being adapted to engage said holder to move said slide into 5 sash engaging position and a projection struck up on said slide near one edge thereof, adapted and arranged to be acted upon

by said lever to move the slide out of sash engaging position.

In testimony whereof, I have hereunto set 10 my hand at Los Angeles, California, this 17th day of February, 1923.

LUTHER HILL.
